UNITED STATES PATENT OFFICE.

LOYAL H. MUDGE, OF DENVER, COLORADO.

BANK-CHECK.

1,109,453.

Specification of Letters Patent.

Patented Sept. 1, 1914.

Application filed August 27, 1912, Serial No. 717,338. Renewed June 19, 1914. Serial No. 846,201.

To all whom it may concern:

Be it known that I, LOYAL H. MUDGE, a citizen of the United States, residing in the city and county of Denver and State of Colorado, have invented certain new and useful Improvements in Bank-Checks; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in bank checks, my object being to provide a device of this character which shall make it more difficult to raise checks or fraudulently alter the same in such a manner as to increase the amount for which the check is 20 drawn. Heretofore, perforators, or stamping machines of various kinds have been employed for this purpose, and while they are exceedingly useful where checks are drawn 25 in offices, they are of no use when a person is away from his office, or to the great number of people who carry pocket check-books.

30 My improvement is of such character that it is equally practicable for pocket and office use, and it consists in providing the check with extensions on both ends, the extension on one end being formed into transverse spaces subdivided to receive numerals indicating the units, tens, hundreds and thousands of dollars, as well as the cents, for 35 which the check is drawn, while the spaces at the opposite end of the check are for receiving the words corresponding to the numerals on the numeral end of the check.

40 The spaces on both ends of the check are provided with indicia, preferably Roman characters, indicating units, tens, hundreds and thousands of dollars, while the usual designation, $\frac{1}{2}$, for cents, is employed. The 45 transverse spaces at both ends of the check may be separated by weakened or perforated lines, or not, as may be desired.

Having briefly outlined my invention, I will proceed to describe the same in detail, 50 reference being made to the accompanying drawing, in which is illustrated an embodiment thereof.

In this drawing: Figure 1 is a face view of a blank check illustrating my improvement. Fig. 2 is a similar view showing the check completely filled out, the amount be-

ing such as to employ one subdivision of each of the spaces at one end of the check, and all of the spaces at the opposite end of the check. Fig. 3 is a check filled out for an amount not requiring the use of all of the spaces at either end of the check, the portions of the check containing the unused spaces being removed as far as possible.

The same reference characters indicate the same parts in all the views.

Let the numeral 5 designate the body of the check, 6 the left-hand extension thereof, and 7 the opposite extension. The end extension 6 is divided by dotted lines 8 into five spaces extending transversely of the check, the said spaces being designated by the Roman characters M, C, X, I, and the character $\frac{1}{2}$, respectively. Each of these transverse spaces is subdivided to form a number of squares 9 adapted to receive numerals increasing consecutively from 1, the unit squares being adjacent the squares containing the aforesaid indicia, or designations. The squares and the spaces designated M, C, X, I, respectively contain numerals dotted or otherwise formed to guide the writer of the check in its preparation. These numerals may be indicated by watermarks in the paper, by dotted lines, or in any other suitable manner. As illustrated in the drawing, the subdivisions of each of the transverse spaces are marked by dotted numerals from 1 to 9, both inclusive, and when one of these spaces has marked in it with ink, a numeral corresponding with that disclosed by the watermark or dots, it designates units, tens, hundreds or thousands of dollars, according as the subdivision is in the I, X, C, or M space.

With reference to the subdivisions or squares of the "cents" space, while these squares are marked to correspond with the markings in the squares of the other spaces, in filling out the check the writer must place in the square designated by the dotted numeral 1, any number of cents for which the check is drawn, from 1 to 19 inclusive; in the square designated by the dotted numeral 2, any number of cents from 20 to 29, both inclusive, and so on, for all of the squares in the cent spaces. It must be noted that a numeral in any square in the X-space indicates tens of dollars, or ten dollars, taken as many times as the numeral contains units, hence the numeral 3 written in the third square of the X-space would indicate thirty

dollars. Again, numerals written in the squares of the I-space indicate dollars in units. This will be understood by reference to Fig. 2 of the drawing.

5 Referring now to the spaces at the right-hand end extension 7 of the check, let the numeral 10 indicate these spaces, the same being designated on the check by the Roman characters *M*, *C*, *X*, *I*, and *¢*, respectively.

10 These spaces are to be filled out with words corresponding to the numerals in the squares, subdivisions, of the end extension 6 of the check.

Where the check requires that a numeral 15 be placed in one of the squares 9 of each space, or column, at one end of the check there must, of course, be a corresponding word or words written in each space 10 at the other end of the check, and consequently 20 no part of either extension will be torn off. However, where the amount is less than one thousand dollars,—see Fig. 3,—the *M*-space, or column, of the extension 6 of the check may be removed, and if the amount of the 25 check does not require that anything be written in the *I*, or cents column, these two columns may be torn off from the extension 7 of the check,—see Fig. 3.

It must be understood that my improved 30 check is equally well adapted for use where any currency system is employed, whether that of the United States or foreign countries. Hence the numerals or other characters placed in the subdivisions of the extension 35 6 of the check may be read in terms of the currency denominations of any system.

At the end 6 of the check, as illustrated in the drawing, the column designations are repeated at the upper edge of the check. This, 40 of course, is not essential, since a single set of designations will answer the purpose. However, the duplication of these column designations may be desirable, since it makes it practically impossible for the writer of 45 the check to place a numeral in the wrong column, though with a single set of designations no difficulty of this character should arise in the case of a check of ordinary width.

50 Attention is further called to the fact that the column designations at the opposite ends of the check are arranged in reverse order, so that when a check is written for less than one thousand dollars, for instance, and does 55 not contain any denomination requiring that numerals be placed in either the *I*-column or the *¢* column, the *M*-column may be removed from the extension or end 6 of the check and the *I*-column and the *¢* column removed 60 from the opposite end of the check. It thus makes it impossible to change the check either up or down, since, while the *M*-column remains on the extension 7 of the check, as 65 there is no corresponding column at the opposite end anything written in the *M*-column

on the extension 7 would have no significance. Again, while the units and cents columns remain on the extension 6 of the check, there are no corresponding columns at the end 7 thereof, consequently anything written in the units and cents column of the extension 6 would have no significance.

Having thus described my invention, what I claim is:

1. A check having extensions at both ends divided into narrow spaces for the reception of writing, said spaces being respectively designated by suitable signs to guide the writer of the check, the order of said signs upon opposite ends of the check and with respect to the middle thereof, being reversed. 75

2. A check having extensions at both ends thereof divided into narrow spaces extending transversely of the check and designated by arithmetical notation signs arranged in a column extending lengthwise of the check and at the lower edge thereof, the spaces at one end of the check being subdivided, the different subdivisions of the various spaces containing inconspicuous numerals from 1 80 to a predetermined higher numeral and on which corresponding numerals are to be conspicuously formed by the writer of the check, while the spaces at the opposite end of the check are adapted to receive words 85 corresponding with the numerals conspicuously formed by the writer of the check on the numeral end thereof. 90

3. A check having extensions at both ends divided into narrow spaces respectively designated by suitable signs to guide the writer 100 of the check, the said signs being the same at both ends of the check but arranged in reverse order with reference to the outermost end of the check. 105

4. A check having extensions at both ends divided into narrow spaces respectively designated by suitable signs to guide the writer of the check, the spaces at each end having their respective signs consecutively arranged, the sign indicating the highest number being outermost at one end of the check and innermost at the opposite end thereof, for the purpose set forth. 110

5. A check having extensions at both ends thereof, divided into narrow spaces extending transversely of the check and respectively designated by suitable signs arranged in columns extending lengthwise of the check and at the edge thereof, the sign designating the space in which are to be written numerals indicating the highest amounts being placed outermost on one end extension and innermost on the other end extension, the denominations of the other spaces being arranged in numerical order, for the purpose set forth. 115

6. A check having extensions at both ends divided into narrow spaces extending transversely of the check and respectively design- 120

nated by the number signs M, C, X, I, ϕ , the M designation at one end of the check indicating the outermost space and at the opposite end of the check, the innermost space,
5 while the other space designations are arranged in numerical order, substantially as described.

In testimony whereof I affix my signature in presence of two witnesses.
